CLAIM

The ornamental design for a medallion, as shown and described.

DESCRIPTION

FIG. 1 is a front top-right perspective view of a medallion showing my new design;

FIG. 2 is a front top-right perspective view of the medallion; FIG. 3 is a front view of the medallion;

FIG. 4 is a rear view of the medallion;

FIG. 5 is a right-side view of the medallion;

FIG. 6 is a left-side view of the medallion;

FIG. 7 is a top view of the medallion; and,

FIG. 8 is a bottom view of the medallion.

The broken lines in the drawings represent portions of the medallion and form no part of the claimed design. The other broken lines in FIG. 2 represent environmental subject matter only and form no part of the claimed design.

1 Claim, 6 Drawing Sheets
